UNITED STATES PATENT OFFICE.

WALTER A. RICHMAN, OF EGG HARBOR, NEW JERSEY.

TOY.

1,388,059.

Specification of Letters Patent. Patented Aug. 16, 1921.

Application filed June 1, 1920. Serial No. 385,691.

To all whom it may concern:

Be it known that I, WALTER A. RICHMAN, a citizen of the United States, residing at Egg Harbor, in the county of Atlantic and State of New Jersey, have invented certain new and useful Improvements in Toys, of which the following is a specification.

This invention relates to improvements in games and toys especially adapted for use as a source of amusement to both young and old.

An important object of this invention is to provide a toy comprising a plurality of communicating inclined runways through which a plurality of marbles or the like are adapted to pass and novel means for controlling the passage of the marbles or the like through the runways.

A further object of the invention is to provide a device of the class described which is simple to operate, desirable in use and cheap to manufacture.

Other objects and advantages of the invention will be apparent during the course of the following description.

In the accompanying drawing forming a part of this application in which like numerals are employed to designate like parts throughout the same,

Figure 1 is a central vertical sectional view through a toy constructed in accordance with this invention.

Fig. 2 is a vertical transverse section taken on line 2—2 of Fig. 1.

Fig. 3 is a fragmentary perspective of the device having a modified form of runway connecting means.

In the drawing wherein for the purpose of illustration is shown a preferred embodiment of the invention, the numeral 10 generally designates the improved toy which comprises an inclined runway 11 which constitutes a magazine for the reception of a plurality of marbles or other spherical objects 12.

As illustrated in Fig. 1, the inclined runway or magazine 11 is curved transversely and has its forward portion bifurcated and soldered or otherwise secured to the upper portion of an inclined runway 14. If desired, the bifurcated forward portion of the magazine 11 may be riveted to the upper portion of the runway 14 so as to provide a secure connection between the parts. The runway 14 is of a greater inclination than the magazine 11 and discharges into a down-

wardly inclined runway 16 at a point adjacent though spaced from the upper end of the same. This provides a means whereby the passage of the spherical objects 12 is somewhat retarded in their movement through the runway for the reason that the spherical objects will roll upwardly and then downwardly upon entering the runway 16. The lower portion of the inclined runway 14 is bifurcated and is secured to opposite sides of the runway 16 so that the spherical objects are accurately directed into the runway 16 and so that a secure connection is provided between the runways 14 and 16. The upper end of the runway 16 is closed and is connected to the upper end of the magazine 11 by a bracing strip 18.

Upon being discharged from the runway 16, the spherical objects 12 enter the upper portion of an inclined runway 20. The lower portion of the runway 16 is bifurcated to form arms 24 which may be secured by any suitable means to opposite sides of the runway 20 so that in addition to securely connecting the parts, the same are retained in alignment. The same is true also of the lower portion of the runway 20 which is provided with spaced arms 26 secured to the opposite sides of the runway 22. The upper or rear end of the runway 22 is closed and is connected to the intermediate portion of the runway 16 by a bracing strap 28 adapted for reinforcing the device.

The spherical objects 12 upon leaving the runway 22 pass through an inclined runway 30 and enter a final discharge runway 32. The upper portion of the runway 30 is securely connected to the runway 22 by bifurcating the forward portion of the runway 22 and soldering or otherwise securing the arms 34 thus formed to the opposite sides of the runway 30. The lower portion of the runway is secured to the intermediate portion of the final discharge runway 32 in a similar manner so that the spherical objects will be positively caused to enter the runway 32 upon leaving the runway 30.

The upper portion of the runway 32 is closed and is connected to the lower portion of the runway 22 by a bracing strap 36. Upon leaving the final discharge runway 32 the spherical objects enter a receiver 40 of elongated formation. The forward portion of the receiver 40 is arranged within

3,019,301. TWENTY-THREE
the discharge end of the runway 32 and is provided with a downwardly extending tongue 42 adapted to be received within a transversely extending slot 44 in the runway 32. In this manner the force of the spherical bodies 12 does not disconnect the receiver 40 from the runway 32 and therefore all of the spherical bodies, upon being discharged from the runway 32 are caused to enter the receiver 40. When all of the spherical bodies have been discharged into the receiver 40, the receiver may be brought up to the magazine 11 for discharging the spherical objects into the magazine. The supporting means for the device comprises legs or standards 46 and 48 arranged beneath the runways and extended outwardly from the same so as to provide a suitable base. The standards or legs 48 are adapted to support the rear portion of the device and are detachably received within sleeves or sockets 50 secured to the supporting strip 28 by a transversely extending connecting member 52. When it is desired to pack the device in a shipping box or the like, the legs 48 may be readily removed so that the device will occupy but a small amount of space. The spherical objects 12 are passed singly through the runways and are released singly through the means of a horizontally pivoted gate 54 having a downwardly extending portion 55 arranged within the upper runway or magazine 11. One end portion of the gate 54 is disposed between and pivoted to a pair of spaced parallel apertured ears 53 formed by bending the upper portion of a strip 56 which, as illustrated in Fig. 2, is secured to one side of the magazine. The horizontally pivoted gate 54 is periodically elevated through contact of one of the spherical objects with a tripping arm 57 carried by an L-shaped crank 58. One limb of the L-shaped crank 58 is extended through a U-shaped supporting standard 61 and has rigid connection with the trip arm 57 so that when the trip arm is engaged by one of the spherical objects the outer limb 59 of the crank will be moved. The outer portion of the outer limb 59 of the crank is connected through the medium of a vertically arranged link 60 with the outer portion of the gate 54 so that when the trip arm 57 is engaged by one of the spherical objects the gate 54 will be momentarily elevated. It will be noted that the weight of the gate, the link 60 and the arm 57 are utilized to normally hold the arm 57 downwardly so that the spherical objects in rolling singly through the runway 16 will engage the trip arm 57 and elevate the same. In the use of the improved toy, all of the spherical objects, with the exception of one, are placed in the magazine 11 rearwardly of the gate 54 and the remaining spherical

object is positioned in the upper portion of the runway 16 so that upon being released the same will roll through the runway and elevate the trip arm 57 for correspondingly elevating the gate 54. The elevation of the gate 54 allows the foremost spherical object 12 to be discharged from the magazine into the upper runway 14 and the trip arm 57 will, by force of gravity, return the gate to its normal or closed position. When the spherical objects which have just been released from the magazine engage the trip arm 57 the same is again elevated for imparting a corresponding movement to the gate 54 which allows the second spherical object to be discharged from the magazine. This continues until all of the spherical objects have been discharged from the magazine through the several runways into the receiver 40. The operation may be repeated by sliding all of the spherical objects 12 from the receiver 40 into the magazine 11. A game constructed in accordance with this invention is simple to operate and in use will be a source of much amusement since the steady movement of the spherical objects through the several runways is highly interesting to watch.

In the modified form of the invention illustrated in Fig. 3 the lower portion of the runway 16 is provided with a pair of spaced connecting arms 66 which are extended through diagonal slots 68 in opposite sides of the runway 20. The ends of the arms 66 are bent flatly in contact with the outer sides of the runway 20 so as to provide a secure connection between the parts. The other runways may of course also be connected in this manner.

It is to be understood that the form of the invention herewith shown and described is to be taken as a preferred embodiment of the same and that such minor changes in construction and arrangement of parts may be made as will remain within the spirit of the invention and the scope of what is claimed.

Having thus described the invention, what is claimed as new is:

1. A device of the class described comprising a plurality of inclined runways having their upper ends closed and their lower ends open, the lower portions of certain of said runways being bifurcated and secured to opposite sides of certain of the other runways at points spaced from the upper ends of the same, and means for controlling the passage of spherical objects through said runways.

2. A device of the class described comprising a plurality of communicating runways, a magazine discharging into one of the runways, a gate pivoted at its forward end and extending across said magazine, a plurality of spherical objects confined within said

magazine by said gate and adapted upon being released to pass through said runways, and a tripping device having connection with the rear end of said gate whereby the 5 gate is elevated when the tripping device is actuated.

3. A device of the class described comprising a plurality of communicating runways, a magazine discharging into one of said runways, 10 a gate pivotally mounted at one end on the side of the magazine and extending across the same, a plurality of spherical objects confined within said magazine by said gate, a tripping device extending across one 15 of said runways, and a rod connecting said tripping device to the free end of said gate whereby the gate is elevated as the tripping device is actuated.

4. A device of the class described comprising a plurality of inclined runways, a magazine discharging into one of the runways, 20 a gate pivoted at one end and extending across said magazine, a gravity actuated tripping device extending across one of said runways and arranged to rock longitudinally of said runway, and a link connecting 25 said gate and said tripping device for elevating said gate when the tripping device is actuated.

30 5. A device of the class described comprising a plurality of inclined runways, a magazine discharging into one of the runways, a horizontally pivoted gate extending across 35 said magazine, a gravity actuated tripping device extending across one of said runways, a link connecting said gate and said tripping device for elevating said gate when the tripping device is actuated, and a receiver arranged at the lower end of the lowermost 40 runway.

6. A device of the class described comprising a plurality of runways, a magazine discharging into one of the runways, a

standard carried by said magazine and having a pair of spaced parallel apertured ears, a gate horizontally pivoted between said spaced parallel apertured ears and extending across and beyond said magazine, a standard carried by one of said runways, a crank rotatably carried by said standard, a gravity actuated tripping device secured to said crank and extending across one of said runways, a link connecting said crank and the extended portion of said gate, and a plurality of spherical objects adapted for passage through said runways for periodically operating said tripping device.

7. A device of the class described comprising a plurality of runways, a magazine discharging into one of the runways, a standard carried by said magazine and having a pair of spaced parallel apertured ears, a gate horizontally pivoted between said spaced parallel apertured ears and extending across and beyond said magazine, a standard carried by one of said runways, a crank rotatably carried by said standard, a gravity actuated tripping device secured to said crank and extending across one of said runways, a link connecting said crank and the extended portion of said gate, a plurality of spherical objects adapted for passage through said runways for periodically operating said tripping device, and a receiver detachably secured to the lower end of the 7 lowermost runway.

8. A device of the class described, comprising runways, a standard carried by one of the runways, a crank supported by said standard, a gravity actuated arm carried 8 by said crank and arranged within one of said runways, and means actuated by said crank for controlling the movement of objects through said runways.

In testimony whereof I affix my signature.
WALTER A. RICHMAN.
